L. SONDEREGGER,
WINDOW CLEANER,
APPLICATION FILED JUNE 21, 1920.

1,359,443.

Patented Nov. 16, 1920.

UNITED STATES PATENT OFFICE.

LEO SONDEREGGER, OF NEW YORK, N. Y., ASSIGNOR OF ONE-HALF TO WILLIAM E. MEYER, OF NEW YORK, N. Y., AND ONE-HALF TO MEYSON MANUFACTURING COMPANY, INC., OF NEW YORK, N. Y., A CORPORATION OF NEW YORK.

WINDOW-CLEANER.

1,359,443.

Specification of Letters Patent. Patented Nov. 16, 1920.

Application filed June 21, 1920. Serial No. 390,505.

To all whom it may concern:

- Be it known that I, LEO SONDEREGGER, a citizen of the United States, and a resident of the city of New York, borough of the Bronx, in the county of Bronx and State of New York, have invented a new and Improved Window-Cleaner, of which the following is a full, clear, and exact description.
- 10 The object of the invention is to provide a new and improved window cleaner more especially designed to permit the user to clean the outer faces of the upper and lower window sashes.
- 15 Another object is to permit of readily placing the window cleaner in position on the window and manipulating the cleaner without requiring undue physical exertion on the part of the operator.
- 20 Another object is to provide a window cleaner which is very simple and durable in construction and is exceedingly light to permit of conveniently handling it on moving it about.
- 25 With these and other objects in view, the invention consists of certain novel features of construction as hereinafter shown and described and then specifically pointed out in the claims.
- 30 A practical embodiment of the invention is represented in the accompanying drawings forming a part of this specification, in which similar characters of reference indicate corresponding parts in all the views.
- 35 Figure 1 is a side elevation of the improved window cleaner with parts in section and shown applied to a window, the latter being shown in cross section;
- 40 Fig. 2 is a sectional plan view of the improved window cleaner on the line 2—2 of Fig. 1;
- 45 Fig. 3 is a rear sectional elevation of the same on the line 3—3 of Fig. 1;
- 50 Fig. 4 is a face view of the wiper; and Fig. 5 is a side elevation of a modified form of the improved window cleaner.
- The main frame 10 of the window cleaner is made approximately U-shaped and comprises inner and outer side arms 11 and 12 and a connecting member 13 connecting the lower ends of the side arms with each other. The connecting member 13 is mounted to turn in a bearing 14 having a base 15 adapted to rest on the top of the window sill 16 and the said base 15 is provided at 55 its rear end with a downwardly extending lug 17 engaging the rear outer edge of the window sill 16 to hold the base 15 and its bearing 14 against sliding inwardly. The front of the base 15 is provided with an 60 upwardly extending flange 18 on which is fastened the upper end of a strap 19 carrying at its lower end a stirrup 20 adapted to be engaged by the foot of the user to securely hold the base 15 and its bearing 65 14 in position on the window sill 16. The lower portion of the flange 18 extends vertically and is adapted to abut against the outer edge of the sill 16 to hold the window cleaner in proper position when cleaning 70 the outer face of the upper sash. It will be noticed that the bearing 14 and its base 15 can be readily moved sidewise on the window sill 16 to a desired position, and then by the operator engaging the stirrup 75 20 and bearing down on the same the bearing can be securely held in the adjusted position on the window sill.
- On the inner side arm 11 is mounted to slide up and down a handle member 25, 80 preferably made tubular, and terminating at its upper end in a handle 26 to permit the operator to slide the handle member up and down on the arm 11. On the outer side arm 12 is mounted to slide up and 85 down a wiping member 30, preferably made tubular, and provided at its upper end with a plug 31 from which extends a supporting rod 32 on which the wiper 33 is mounted to swing on a suitable pivot 34. The 90 wiper 33 is preferably of rectangular shape and is provided with a covering of chamois or other suitable wiping material. It will be noticed that the wiper 33 can rock sideways on the pivot 34 to insure proper cleaning of the outer face of the window pane. The supporting rod 32 is provided near its lower end with an inwardly extending offset 35 to engage the wiper 33 with the outer 95 face of the window pane and without the 100

wiping member 30 and the outer side arm 12 coming in contact with the frame of the window sash.

The lower end of the handle member 25 is provided with a collar 40 on which is pivoted a link 41 extending transversely above the window sill 16 and below the lower sash to be cleaned, which is in partly opened position. The outer end of the link 41 is pivotally connected at 42 with a lever 43 fulcrumed at 44 on the connecting member 13 to swing up and down. The outer end of the lever 43 is connected by a link 45 with a collar 46 arranged on the lower end 15 of the wiping member 30.

When the handle member 25 is moved upward by the operator then the link 41 imparts an upward swinging movement to the lever 43, which by the link 45 imparts a 20 similar upward sliding movement to the wiping member 30 and consequently to the wiper 33, and during this movement the operator by swinging the handle member 25 sidewise imparts a similar sidewise swinging movement to the U-shaped frame 10 and consequently to the wiping member 30 and its wiper 33 to move the latter sidewise on the outer face of the window pane to clean the same. When the operator moves the 25 handle member 25 downward a similar downward movement is given to the wiping member 30 and its wiper 33. By reference to Fig. 1, it will be noticed that the connecting link 41 is made segmental to permit of lowering the window sash sufficiently for the wiper 33 to reach the upper portion of the window pane when manipulating the window cleaner, as above described. The lever 43 is also preferably provided with an 30 offset, as shown in Fig. 1, to hold the lever out of contact with the bottom rail of the window sash when the latter is moved into lowermost position.

In the modified form shown in Fig. 5, the 35 lever connection between the handle and wiping members 25 and 30 is by the use of a lever 50 fulcrumed at 51 on the lower portion of the outer frame arm 12, and the inner end of this lever is pivotally connected by a link 52 with the handle member 25 while the outer end of this lever is connected by a link 53 with the wiping member 30. The action of this lever connection is the same as above described in reference to the 40 lever 43 and its links 41, 45 so that further description of the same is not deemed necessary.

It will be noticed that by the arrangement described the operator can readily place 45 the window cleaner in position on the window and move the same sidewise on the window sill for the wiper to reach every part of the window pane on the operator moving the handle member 25 up and down and 50 sidewise. It will also be noticed that on

moving the sash up and down to a desired position and correspondingly adjusting the window cleaner every part of the sash pane can be thoroughly wiped by the wiper 33.

The window cleaner shown and described 70 is composed of comparatively few parts and hence is extremely light to permit the user to conveniently move the window cleaner from one window to another and to adjust the window cleaner on each window as above 75 explained.

Having thus described my invention, I claim as new and desired to secure by Letters Patent:

1. A window cleaner, comprising an approximately U-shaped frame having inner and outer members and a connecting member connecting the inner and outer members with each other, the side members being adapted to straddle a window sash, a handle member slidable on the said inner frame member and under the control of the operator, a wiping member slidable on the outer frame member and provided with a wiper to wipe the outer face of the window 90 sash, and a lever connection connecting the said handle member with the said wiping member and extending across the window below the window sash.

2. A window cleaner, comprising an approximately U-shaped frame having inner and outer members and a connecting member connecting the inner and outer members with each other, the side members being adapted to straddle a window sash, a handle member slidable on the said inner frame member and under the control of the operator, a wiping member slidable on the outer frame member and provided with a wiper to wipe the outer face of the window 95 sash, a lever fulcrumed on the lower portion of the said frame, a link connecting one end of the said lever with the said handle member, and a link connecting the other end of the lever with the said wiping member.

3. A window cleaner, comprising an approximately U-shaped frame having inner and outer members and a connecting member connecting the inner and outer members with each other, the side members being 110 adapted to straddle a window sash, a handle member slidable on the said inner frame member and under the control of the operator, a wiping member slidable on the outer frame member and provided with a wiper to 115 wipe the outer face of the window sash, a lever connection connecting the said handle member with the said wiping member and extending across the window below the window sash, a bearing adapted to rest on the window sill and on which the said connecting frame member is pivoted, and a stirrup on the said bearing to hold the same in place 120 on the window sill.

4. A window cleaner, comprising an ap- 130

proximately U-shaped frame having inner and outer members and a connecting member connecting the inner and outer members with each other, the side members being adapted to straddle a window sash, a handle member slideable on the said inner frame member and under the control of an operator, a wiping member slideable on the

outer frame member and provided with a wiper to wipe the outer face of the window sash, the said wiper being mounted to rock sidewise, and a lever connection connecting the said handle member with the said wiping member and extending across the window below the window sash.

LEO SONDEREGGER.
